UNITED STATES PATENT OFFICE.

EDMUND C. MORGAN, OF CHICAGO, ILLINOIS.

MINING AND LOADING MACHINE.

Patented May 18, 1920.

1,340,731.

Specification of Letters Patent.

Application filed August 4, 1913, Serial No. 782,766. Renewed June 17, 1918. Serial No. 240,524.

To all whom it may concern:

Be it known that I, EDMUND C. MORGAN, a citizen of the United States, residing at Chicago, in the State of Illinois and county of Cook, have invented certain new and useful Improvements in Mining and Loading Machines, of which the following is a specification.

My invention relates to improvements in mining and loading machines, more particularly, though not necessarily, adapted for the purpose of entering the mine room and breaking loose and removing the coal or other material from the mine after the kerfs, which divide the body of the vein into large blocks, have been cut.

One of the objects of my invention provides an improved machine of this character which will be simple, durable and reliable in construction and effective and efficient in operation. Other objects of my invention will appear hereinafter.

Referring to the accompanying drawings:

Figure 1 illustrates a machine in elevation embodying my invention, the machine being positioned in the mine room and in the act of breaking loose and removing material therefrom.

Fig. 2 is a top plan view of the machine illustrated in Fig. 1.

Fig. 3 is a transverse vertical section substantially on the line 3—3 of Fig. 2.

Fig. 4 is a transverse vertical sectional view substantially on the line 4—4 of Fig. 2.

Fig. 5 is a detail top plan view of the mechanism immediately below the main platform, the main platform being shown in dotted lines to illustrate its position relative to the other parts.

Fig. 6 is a bottom plan view of the main platform, and

Fig. 7 is a perspective view of the shovel.

The machine which I have illustrated in the drawings and which constitutes one embodiment of my invention, is more particularly designed for handling coal, and I will describe my invention in connection with the machine shown for this purpose, but it will be obvious to those skilled in the art, after having obtained an understanding of my invention from the disclosures herein made, that my invention is equally as well adapted to the handling of various other kinds of materials and that the structure 55 may be modified to meet the requirements of

such other materials without departing from the scope and spirit of my invention.

In mining coal it is desirable to cut a plurality of kerfs in the vein or body of the material to be mined at various angles to each other so as to divide the vein into large regular and uniform blocks of coal. The particular machine shown in the drawings is intended to operate upon these large divisions or blocks of coal which have been formed by the cutting of the kerfs. By way of example I have illustrated, diagrammatically, a mine room or entry A in which a series of large blocks of coal have been formed by the cutting of numerous kerfs, these blocks being in condition to be removed from the mine in order to make room for the cutting, by a mining machine, of another series of kerfs to form another series of blocks of coal. These blocks B of coal are formed, in this instance, by the cutting of three horizontal kerfs C, vertical kerfs D, and a rear vertical kerf E. The horizontal kerfs C extend into the vein or body of coal and from side wall to side wall of the mine room. One of these horizontal kerfs is formed along the upper line of cleavage, another along the lower line of cleavage or floor of the mine room, and a third intermediate of the other two. The lower horizontal kerf C is preferably gripped or slightly inclined downwardly with respect to the floor of the mine in order that the apparatus may enter the kerfs to break loose and remove the coal without scraping the floor of the mine, this slight inclination being clearly indicated in Fig. 1 of the drawings. The intermediate horizontal kerf C may, and generally does, lie in a plane substantially parallel with respect to the floor of the mine, but in this particular instance I have illustrated it (see Fig. 1) as being slightly inclined downwardly toward the forward end of the blocks in order that, as will hereinafter appear, the upper blocks of coal may be conveniently removed.

The horizontal kerfs are preferably cut first and as they are being cut a plurality of flat portable supports or platforms F are placed at intervals in the intermediate and lower kerfs to take the place of the material removed by the kerf-cutting machine in order to support the undercut coal and prevent it from dropping of its own weight until it is to be removed. After the hori-

zontal kerfs have been cut and the supporting platforms placed in position the vertical kerfs D are cut. These vertical kerfs are positioned between the series of supporting 5 platforms so that the blocks of coal projecting from the face or body of the mine are supported upon individual supporting platforms. It will be noted more particularly by reference to Fig. 2, that the supporting 10 platforms are somewhat narrower in width than the width of the blocks of coal so that, as will hereinafter appear, the shovel may enter the kerfs and engage the blocks of coal. The cutting of the horizontal and vertical 15 kerfs C and D leaves the blocks severed on all of their sides except their rear ends, which are attached to the body of the vein, and when these blocks are to be removed they may be broken loose substantially along 20 the line E' from the body of the vein. Sometimes an intersecting vertical kerf E is cut at the inner ends of the blocks and extending upwardly and downwardly from the intermediate horizontal kerfs in order to 25 weaken the undercut portions E' and insure the breaking of this undercut portion along more or less definite lines.

The machine illustrated in the drawings is intended to break loose or dislodge and remove 30 the blocks formed after the cutting of these kerfs. This machine is preferably adapted to travel along suitable tracks 1 properly laid so that the machine will be positioned with proper relative position to 35 the blocks to be removed, and it is intended to transfer the blocks from their resting position to suitable cars 2, also adapted to run on tracks properly disposed relatively to the machine. The entire machine is 40 mounted upon a suitable traveling truck 6 having suitable wheels 3 mounted in pairs on axles 4, and may be propelled along the track by means of a motor 5 substantially beneath the traveling truck platform 6, the 45 motor being connected, by suitable gears 7, with one of the wheel axles. The working and coal handling parts of the machine are all supported by a main frame 8 which is pivotally mounted upon the truck platform 6 so 50 that the working parts may be swung or rotated in a horizontal plane to adapt them to the particular requirements of the positions in which the coal is disposed, a suitable pivot being formed by means of a 55 depending projection 9 from the frame 8 which passes through and is journaled in the center of the truck platform 6. The truck platform is preferably circular and provided with gear teeth on its periphery 60 to form a large gear. The platform 8 carries, in a suitable bearing, a short vertical shaft having a pinion 10 on its lower end in mesh with and adapted to travel around the large gear formed by the truck platform 65 so that rotary motion may be imparted

to the frame 8 and the parts supported thereby. This gear 10 may be driven in any suitable manner, such for instance, as a motor 11 supported upon the platform 8, and adapted to drive the shaft or pinion 10 70 by means of the beveled gears 12, seen clearly in Figs. 1 and 5. Immediately above and substantially parallel with the frame 8 and truck platform 6 is a large platform 13 which is pivoted at 14 in suitable bearings 75 on the frame 8 so that the platform may be tilted or swung vertically. This platform is mounted in this manner so that it may be inclined at various angles with respect to the coal to be removed; that is to say, it is 80 arranged in this manner so that it may be raised or lowered to position it in a plane substantially parallel to planes in which the intermediate and lower horizontal kerfs C are cut, the planes of the kerfs, as before 85 mentioned, being slightly inclined, so that the blocks of coal, after being dislodged and raised or lowered as the case may be to the same level may travel in substantially a given plane until they reach the cars 2. 90 While it is obvious that any suitable mechanism for raising and lowering the platform may be employed, I have illustrated in the drawings one form of mechanism by which this may be accomplished. The frame 8 has 95 an elongated horizontal bearing 15 (Fig. 5) in which is journaled a shaft 16 disposed immediately below the platform 13. This shaft carries a couple of crank arms 17, which carry rollers 18 at their ends. The 100 platform 13, as seen in Figs. 1 and 5, rests upon these rollers, and by actuating the shaft 16 to swing the crank arms the platform 13 may be raised and lowered about its pivot 14. This shaft is shown as being 105 driven by the worm gear 19 and worm 20 from the motor 21. The motor 21 is mounted upon a laterally extending arm 22 of the frame 8, and carries, in suitable bearings thereon, a counter-shaft 23, one end of which 110 carries the worm 20 and the other end of which has a gear 24 which meshes with and is driven by a similar gear 25 on the motor shaft. The provision of the worm gear 19 and worm 20 eliminates any necessity of 115 providing extra locking means for holding the platform in any position to which it is raised or lowered, for the reason that this worm gearing will remain in any position in which it is placed. The platform 13 supports a sub-frame G, which is arranged to slide or reciprocate longitudinally upon the platform 13. This frame is composed of two vertical side plates 30 and a horizontal plate 31 across the top of said vertical plates 120 to form a bridge over the central portion of the platform 13, and thereby provide a large clear open space through which the blocks of coal may pass on their way to the cars 2. 125 The lower ends of the vertical plates 30 130

have lateral base plates 32 which slide upon the platform 13 and which are carried along a definite line on said platform 13 by means of the ribs 33 engaging suitable guide slots 34 in the upper face of the platform 13. Additional guides are provided at 33', 33''. In the drawings I have shown a simple mechanism for shifting or sliding this sub-frame G along the platform 13. The platform 13 has two forwardly extending arms 36 and these extensions have laterally projecting lugs 37 at their outer ends. Similar lugs 38 are also formed at the opposite end of the platform, as shown clearly in Fig. 6. Cables or ropes 39 are provided at each side of the platform and these cables are anchored to the lugs 37 and 38 on corresponding sides of the platform, as shown in Fig. 2. The cables 39 pass around small sheaves 40 or guide-pulleys 40 and loop upwardly around winding drums or sheaves 41 which are disposed at the top of the sub-frame. The small pulleys 40 are mounted upon the edges of the lateral base plates 32 of the sub-frame, hence it will be obvious that by rotating the winding drums 41 the sub-frame may be readily shifted or slid in either direction along the platform 13. The drums or sheaves 41 are carried upon opposite ends of the shaft 42 which extends across and has bearings 43 in the upper end or top of the sub-frame G, as clearly shown in Figs. 3 and 4. This shaft is driven from a counter-shaft 44 by means of a chain or rope 45 which passes around a suitable pulley 46 on the shaft 42 and a pulley 47 on the counter-shaft 44. The pulley 47, however, is loose on the shaft 44 and it may be connected to or disconnected from said shaft in any suitable manner, such for instance, as by means of an ordinary clutch. In the drawings I have shown a clutch member 48 which is keyed to rotate with the shaft 44 but to slide longitudinally thereof, and this may be shifted to or out of engagement with the pulley 47 to connect the pulley with or disconnect it from the shaft, by means of a hand-lever 49. The shaft 44 is journaled in one of the vertical plates 30 of the sub-frame and in a bearing standard 50 rising from the base of the sub-frame. This shaft is driven from the main shaft 51 through the medium of a worm 52 and worm gear 53. The main shaft 51 is driven from a motor 54 through the medium of the gears 55, the motor being mounted upon one of the sub-frame lateral plates 32 to travel therewith. The main shaft is journaled in a bearing standard 56 rising from the sub-frame base 33, and also in bearings 57 formed on the motor 54. Other mechanism is driven from the main shaft 51, and hence I prefer to arrange this counter-shaft 44 so that it may be thrown into and out of operation at will. Any ordinary clutch may be used for this purpose. In the drawings, the worm 52 is rotatable on the main shaft 51 and is arranged to be connected with or disconnected from said shaft by means of a sliding clutch member 58 which is keyed to rotate with the shaft. This clutch member 58 is adapted to be shifted into or out of engagement with the worm 52 by means of a suitable hand-lever 59 pivoted at 60 to the base of the sub-frame. At the forward end of the horizontal sliding plates 32, which form the base of the sub-frame, is a substantially vertically disposed inverted U-shaped frame comprising two parallel legs or members 65 which are joined together at their upper ends by the cross-bars or members 66. This frame is pivoted at 67 in lugs 68 which depend from the under side of the members 32 of the sub-frame so that the frame may be rotated within limits about its pivots in a vertical plane, as indicated by dotted lines in Fig. 1. Since this U-shaped frame is supported by the sub-frame it necessarily travels therewith. In order that the frame may be conveniently oscillated or rotated about its pivot 67 I provide a winding drum 69 upon which a cable 70 is wound, one end of the cable being anchored to a lug 71 on the upper end of the U-shaped frame 65. This cable drum is mounted upon a shaft which is journaled in one of the vertical plates 30 of the sub-frame G and in the bearing standard 56 (Figs. 1 and 2) and is adapted to be driven from the main shaft 51 through the medium of the worm 72 and the worm gear 73. The worm 72, however, is loose on the shaft 51 and is adapted to be connected with or disconnected from the shaft by means of the sliding clutch member 74, which clutch member is keyed to slide upon the shaft. The clutch member 74 may be conveniently shifted by means of the hand-lever 75 pivoted upon the base of the sub-frame. This mechanism for swinging the U-shaped frame about its pivot is preferred for the reason that the load comes upon the frame at one side of its pivot thereof and it is simply necessary to wind up or ease off the cable 70 against the action of gravity acting upon the load and the parts supported by the frame. The U-shaped frame carries a shovel member S which projects forwardly from the frame at substantially right angles thereto, and which is arranged to slide or reciprocate vertically in said frame. Accordingly the rear end of the shovel (Fig. 7) has a vertically disposed guide member 75 disposed on each side and these guides, as will be seen clearly in Fig. 3, are adapted to slide in guideways or slots 76 on the inner faces of the side members 65 of the U-shaped frame. The bottom end of the frame is open so that the shovel may be dropped or lowered to a point very close to the floor 130

of the mine so that it may enter the lowermost horizontal kerf, and its range of movement in a vertical direction is sufficient to enable it to be positioned in any of the horizontal kerf below the uppermost horizontal kerfs. It will be noted that the U-shaped frame and its shovel are all positioned within the confines of the projections or extensions 36 on the platform 13, and the purposes of the extensions 36 are simply to increase the distance to which the sub-frame, the U-shaped frame and shovel may be moved forwardly on the platform 13. This shovel is adapted to be raised and lowered 15 in its guide frame by means of suitable hoisting mechanism, such as shown in the drawings. This hoisting mechanism comprises the worm 77, worm gear 78, belt or chain 79, shaft 80, winding drums 81 and cables 82. The winding drums 81 are mounted upon the shaft 80, which shaft is journaled in bearings in the cross bars 66 of the U-shaped frame, and the cables 82 are fastened at their lower ends 83 to the guides 25 75 of the shovel and are adapted to be wound upon or unwound from the drums 81 to raise and lower the shovel. The worm gear 78 is mounted upon a stud shaft 84 outstanding from one side 65 of the U-shaped frame, and this shaft, together with the shaft 80, carries pulleys around which the chain or belt 79 passes to impart motion from the shaft 84 to the winding drum shaft 80. The worm 77, which drives the worm 30 gear 78, is mounted upon an extension 85 and this extension is connected to the main shaft through the universal joints 86, as shown clearly in Figs. 1 and 2, so that the worm gear 78 may be driven at any angle 40 to which it is positioned by the swinging of the U-shaped frame. One member of one of the universal joints 86 is loosely rotatable on the end of the main shaft 51 and is adapted to be connected with or disconnected from said shaft by means of the clutch member 87 so that the raising and lowering of the shovel may be controlled at will. The clutch member 87 is, like the clutch members previously described, keyed 45 50 to slide on the shaft 51 and is adapted to be manipulated by means of the hand-lever 88 pivoted upon the base of the sub-frame. The scoop or shovel S comprises two side members 89 (Fig. 7) and bottom members 55 60 65 70 75 80 85 90 95 100 105 110 115 120 125 130 90, the latter being spaced apart to form an open slot 91 therebetween. They are connected at their rear ends by a bridge piece 92. The forward ends of the shovel are entirely open so that the blocks of coal 60 may be conveniently shifted therethrough. The side members 89 of the shovel are preferably spaced apart substantially the distance that the vertical kerfs D are spaced apart so that these sides may enter the horizontal kerfs. The bottom members 90 of

the shovel are adapted to enter the horizontal kerf, and, as shown in Fig. 2, to form ledges or shelves which engage the lower portions of the faces of the blocks of coal which project beyond the supporting sleds 70 or platforms F. The slot or opening 91 formed between the bottom members 90 of the shovel is sufficiently wide to permit the portable supports F to enter therein and to be removed through the rear end of the shovel after the shovel has been moved forward into position to engage and hold the blocks of coal. It will be noted that the bridge portion 92 at the rear end of the shovel is depressed so that its upper surface 80 lies in the plane of the bottom faces of the members 90 in order to permit the portable supports to readily pass over it, and the platform 13 has a groove or slot 93 which registers with the slot in the shovel and likewise permits further withdrawal of the portable supports F. The forward ends of the side members 89 and the bottom members 90 of the shovel, as will be noticed in Fig. 7, are rounded so that they may be readily entered into the kerfs surrounding the blocks of coal to be removed.

After the shovel and its frame and the sub-frame have been moved forward until the shovel has entered the kerfs in position 95 to embrace the particular block to be removed, as shown in dotted lines in Fig. 1, the portable supports or platforms F may be withdrawn, as above described, and the block of coal allowed to drop upon the 100 shovel and break loose along the uncut portion E' of its own weight. The shovel with its block of coal thereupon may then be withdrawn by shifting its frame and the sub-frame, and then lowered in the U-shaped 105 frame until its bottom members 90 are in line with the upper surface of the platform 13, or, if desired, the block of coal may be broken loose or dislodged in any other suitable manner without removing the supporting platform F, said supporting platform F remaining in position after the shovel has been withdrawn with the block upon the shovel. In the drawings I have shown several ways by which the coal may be dislodged. It will be noted by reference to Figs. 1 and 2 that the sub-frame G has a rearwardly projecting horizontal arm 100 which is positioned above the car 2 and which projects beyond the opposite edge thereof, and this 110 arm carries at its outer end a large sheave or pulley 101 around which a cable 102 passes. One end of the cable passes around a winding drum 103 on the counter-shaft 44 by means of which drum the cable may be 115 wound up. The other end of the cable passes through the sub-frame and U-shaped frame to the particular block of coal which is to be removed, to which block it may be temporarily fastened or anchored in any 120 125 130

suitable manner, such, for instance, as by means of the branch cables or yoke 104 which embrace the block of coal and carry hooks 105 at their ends for engagement 5 with the rear end of the block. Thus after the shovel has been positioned in the kerfs the cable may be attached to the block of coal and by actuating the winding drum to pull the cable the block of coal may be dislodged from the body of the vein and drawn 10 from the shovel, after the shovel has been withdrawn and positioned in line with the platform 13, along the platform 13 and on to the car 2, as indicated in dotted lines in 15 Fig. 2. This cable may also be used to withdraw the portable supporting platform F, as above described when the coal is to be allowed to drop upon the shovel instead of being broken loose by the cable. 20 The winding drum 103 is loosely rotatable upon the countershaft 44 but may be connected therewith or disconnected therefrom by means of the clutch member 106 which, like the other clutches above described, is 25 keyed to slide on said shaft and which may be manipulated by means of the hand-lever 107.

It might be, under certain conditions, inadvisable to break the coal loose by allowing it to drop of its own weight or by pulling it away from the body of the vein by the cable 102, as above described. In the dotted lines in Fig. 1 I have illustrated how the shovel itself may be manipulated to supply sufficient force to break the block loose 35 along the uncut portion E'. It will be seen that after the shovel has been inserted in the kerfs and in engagement with the block, it may be raised in its guideway a slight 40 amount and at the same time the U-shaped frame may be allowed to swing on its pivot 67 by easing off on the cable 70 so that the frame and the shovel will assume positions substantially like that indicated by the dotted lines 110 (Fig. 1). The force exerted 45 by the shovel in moving upward in its guide frame will tilt the front end of the block upward, as shown in dotted lines 111, and thereby break the block of coal loose along the uncut portion E'. In this manner the 50 block may be dislodged without the aid of the hauling cable 102, but the hauling cable may be afterward attached to the block to draw it from the shovel along the platform 55 13 and onto the car 2.

The operation of the loading machine described above may be effected at any desired location inside or outside of the mine, but it is particularly adapted for operation 60 inside of a mine, as illustrated in Fig. 1. After the truck is moved along the rails onto the proper location in the mine tunnel A, the electric motor is operated in one direction or another by means of suitable electric switches, including if desired an elec-

tric reversing switch. The operation of the motor 11 effects the rotation of the pinion 10 on the large gear 6 and thus rotates the frame 8 on the pivot 9 to any angular position with respect to the face of the mine 70 wall where the kerfs D have been made by a kerf cutting machine, as illustrated in Fig. 2.

By operating the electric motor 21 to effect the turning of the shaft 16, the lever 75 17 and the roller 18 may be moved upwardly so as to tilt the frame 13 on the pivot 14. In this way, the plane of the lower part of the carrier S may be adjusted so as to be substantially parallel with the 80 planes of the horizontal kerfs in the mine wall, as illustrated in Fig. 1. The electric motor 21 may also be provided with the usual electric switches, including a reversing switch, and the worm gearing 19 and 20 85 may be depended upon to lock the apparatus in adjusted position, so that the weight of the frame 13 will not turn the motor shaft back to initial position when the current from the motor is cut off. 90

The operation of the electric motor rotates the shaft 51 which is provided with a plurality of clutches, as shown in Fig. 1, for transmitting motion to various parts. The operation of the clutch 87 will effect 95 the rotation of the shafts 84 and 80, as shown in Fig. 1, which will in turn operate the rope drums 81, as shown in Figs. 2 and 3, to lift the carrier S while the guide 65 holds the latter substantially horizontal. 100 When the carrier reaches the proper position, the clutch 87 may be released and the worm gearing relied upon to hold the carrier in its proper elevated position. Now by operating the clutch 58, the rope gear feeding mechanism at the sides of the inverted U-shaped frame G will feed forward the supplemental frame together with the vertical guides 65 and the carrier S. In this manner the carrier can be moved into the 110 kerfs in the mine wall, the block F being straddled, as shown in Fig. 2. After the carrier S has been moved forward a sufficient distance, the clutch 58 may be released and the clutch 74 then operated to tilt the 115 vertical guides, together with the carrier, as illustrated by the dotted lines at the right hand portion of Fig. 1. It should also be observed that at this step in the operation, the horizontal platform 18 may be tilted 120 upwardly by operating the motor 21. It is preferred, however, to rely on the rope 70 for tilting the carrier, and thereby breaking loose from the mine wall a large block of material. It should be observed, however, 125 that the tilting of the carrier may not always be necessary, because, in some instances, the weight of the block of material is sufficient to break itself loose from the mine wall or it may be pried loose manually. 130

After the block of material is dislodged from the mine wall, and the carrier has been brought into proper position in the kerfs, it may be lifted slightly and then retracted 5 and brought to a position where it will register with the passageway through the frame G. The pivoted platform 18 may then be tilted upwardly a sufficient distance to cause the block of material to slide off the carrier 10 and through the frame G onto a mine car 2. I prefer, however, to provide means for positively pulling the material off the carrier while the latter is being held stationary in its initial position. As shown in Fig. 2, 15 hooks 104, 105 are provided for engaging the block of material, so that it will be positively pulled onto the mine car when the clutch 58 is operated, and the clutch 106, as shown in Fig. 4, also operated. The clutch 20 58 may be thrown in and left in, and the clutch 48 (Fig. 4) relied upon to control the longitudinal movements of the supplemental frame, and the clutch 106 used for controlling the block-pulling mechanism. 25 Whenever the worm gearing is of such pitch that it acts as locking devices, the motor 54 may be provided with a reversing switch in the well-known manner, so that the supplemental frame may be retracted and the rope 30 drum 69 operated so as to permit the guide frame 65 to be moved back to its initial position. Also by the reversal of the motor 54 the carrier S may be lowered to its initial position where its carrying surfaces 90 will 35 register with the passageway through the supplemental frame.

After a block of coal has been dislodged and removed, the carrier S may be lowered to the floor of the mine, or nearly so, and 40 then moved forwardly around the platform F until the proper position is obtained for the dislodging of the lower block of coal. The exposed lower ends of the platforms may be beveled, and so also the forward 45 end of the cross piece 92, so that the latter may easily pass beneath such exposed ends of the platform F, particularly when the carrier enters an undercut. If desired, the platform F may be so inserted into undercut 50 cuts that by means of wedges beneath the platforms the exposed ends will be a short distance above the floor of the mine, so as to facilitate the insertion of the cross piece 92 beneath the platform. After the cross 55 piece 92 is inserted beneath the platform F and the carrier is lifted, the block of coal will be broken away from the mine wall. Now, by partially withdrawing or retracting the carrier, the cross piece 92 may be 60 placed in position to clear the platform F, and then by elevating the carrier the block of coal may be lifted and removed to a position where it can be moved to the mine car, as before explained, the platform F being 65 left on the floor of the mine in convenient

position for use elsewhere when subsequent kerfs are cut in the mine wall.

It is preferred to pivot the platform 13 at 14 to the rotatable frame 8, so that adjusting mechanism may be used for lifting 70 and lowering the platform 13 and bringing its upper surface in a plane substantially parallel to the planes of the horizontal kerfs. The forward movements of the carrier into the kerfs will then be obtained with facility. 75 The platform 13 serves as a track for the reciprocating frame G, and therefore after the carrier S has been adjusted as to elevation and as to horizontal position, it may be moved forwardly into the kerfs without 80 any undue friction, which might be caused if the nose of the carrier were inclined downwardly and dug into the solid mass of the coal. The platform 13 may have its forward end inclined slightly upwardly, however, within the limits of the thickness of the platform F, so that the plates 90 of the carrier will not engage the lower edge of the block of coal B when the carrier S is 85 thrust forward into the kerfs of the mine 90 wall. The rearward inclination of the platform 13 may then be taken advantage of to facilitate the removal of the block of coal over the reciprocating frame between the vertical plates G. However, I prefer to adjust the inclination of the platform 13 so 95 that the carrier S may be inserted into the kerfs in the mine wall with minimum friction, which is obtained when the platform 13 is substantially parallel to the average 100 plane of the horizontal kerfs.

The horizontal kerfs may be produced simultaneously in the mine wall, or the undercut may first be made and the uppercuts successively afterward, the platforms being 105 inserted at intervals in the undercut before the next upper cut is made. Therefore, when there is any danger of the coal being broken down when horizontal kerfs alone are made, the coal will be held up by means 110 of the platforms if the undercut is made first and the platforms inserted therein at intervals, before the uppercuts are made. Ordinarily, however, the horizontal kerfs may be simultaneously cut without danger 115 of the coal breaking down. The platforms may then be inserted in the undercut and the intermediate cut at the desired intervals, as shown in Fig. 2 by the dotted line positions F. After the horizontal kerfs are 120 made and the platforms inserted at the proper points or predetermined positions, the vertical kerfs D may be made either singly or a plurality at a time. It will be evident that after the vertical kerfs are 125 made the platforms will retain the blocks of coal in position to permit the carrier S to be operated as hereinbefore described.

It should also be noted that since the machine is pivotally mounted to turn on an 130

upright axis on the truck, the scoop S may be swung around at right angles to the position shown in Fig. 1 so that the truck propelling mechanism may be used to force the 5 scoop under material to be loaded. The scoop is open at its rear end and when in its initial position forms a continuation of the trough or chute formed by the walls G and the upper surface of the platform 13 between said walls. By referring to Figs. 10 3, 4 and 7 it will be seen that the part 92 connecting the horizontal spaced-apart members 90 is adapted to extend into the trough 93 so as to be guided along the lat- 15 ter and thus keep the scoop in alinement with the passageway between the walls G. The unloading mechanism is of course operable independently of any forward movement of the scoop because the material may 20 be pulled out of the rear end of said scoop even when the latter is in stationary position while in registry with said chute. However, when desired the scoop may be again started forward while the block of material 25 is moved off the scoop. Therefore, the scoop may be reciprocated while occupying various angular positions and while unloading cores out of the rear end of said scoop into the forward end of the chute and longitudinally along the latter to loading position. 30

Obviously, those skilled in the art may make various changes in the details and arrangement of parts without departing from the spirit and scope of my invention as defined by the claims hereto appended, and I desire, therefore, not to be restricted to the precise construction of the apparatus herein disclosed.

Having thus described an embodiment of 40 my invention, what I claim and wish to secure by Letters Patent of the United States is:

1. In a loading machine, the combination with a carrier, of framework for supporting 45 said carrier, upright guides on said framework for said carrier, means for shifting said carrier bodily up and down in said guides to position it with respect to the material to be taken from a mine wall, means for shifting said carrier together with said guides in a generally horizontal direction into the mine wall for taking a block of material directly therefrom and moving it back to a 50 predetermined position relatively to said framework, and means acting directly on the block of material on said carrier to slide the same off of said carrier and over said framework into position for loading.

2. In a loading machine, the combination 60 with a horizontally traveling support, of a vertical frame pivoted thereto, a carrier supported by said frame and movable therewith into position to take a block of solid material directly from its position in a mine in its native bed, means for lifting and lowering 65

said carrier relatively to said frame and said support to present said carrier at the desired height with respect to the material to be loaded, means for tilting said frame with the carrier thereon to cause said carrier to 70 dislodge the solid block of material directly from its position in its native bed, and means for controlling the operation of said frame and carrier to secure movements relatively to said traveling support to effect the 75 dislodgment of said material and the movement thereof back from the mine wall toward loading position.

3. In a loading machine, the combination with a main frame, of a supplemental vertical frame pivoted thereon, a carrier supported by said supplemental frame free from obstructions between any vertical position of the carrier and the mine wall and movable with said supplemental frame horizontally into the mine wall to receive a block 80 of material directly therefrom, means for lifting and lowering the carrier vertically free from any obstruction between the same and the mine wall to present the carrier at 85 the desired height with respect to the block of material to be taken directly from the mine wall, means for tilting the carrier against the block of material to dislodge the same from the body thereof, and apparatus 90 for moving the material from the carrier 95 toward loading position.

4. The combination with a traveling support, of a frame pivoted thereto, a carrier supported by said frame and movable therewith to a position to take on a load, means for lifting and lowering the carrier to present it at the desired height with respect to material to be loaded, means for tilting the carrier to dislodge a portion of the material 100 from the body thereof, and hauling mechanism for hauling the load from the carrier 105 to a predetermined position.

5. The combination with a traveling truck, of a hinged platform mounted thereon, a reciprocating frame mounted on said hinged platform, a tilting frame pivoted to said reciprocating frame, a carrier mounted in said tilting frame, means for lifting or lowering said carrier in said tilting frame, mechanism for holding said tilting frame in adjusted position, apparatus for effecting the operation of said reciprocating frame, means for moving said hinged platform up or down, and hauling mechanism for transferring the load from the carrier to a point off the reciprocating frame. 110 115 120

6. The combination with a platform adapted to be inserted into horizontal kerfs in a mine wall to support slabs of material produced by a plurality of vertical kerfs at angles to said horizontal kerfs, of a carrier, means for moving said carrier into said kerfs around one of said platforms, and mechanism for tilting said carrier to dis- 125 130

lodge the block of material above the platform with which said carrier is associated.

7. The combination with a supporting frame, of a platform pivotally mounted thereon, means for lifting or lowering the forward end of said platform, a reciprocating frame guided on said platform for longitudinal movement thereon, apparatus for moving said reciprocating frame to advance or retract the same, a tilting frame mounted on said reciprocating frame and movable therewith, a carrier vertically movable in said tilting frame, and means for withdrawing material from said carrier over said reciprocating frame.

8. In a loading machine, the combination with a carrier, of an upright frame for guiding said carrier and confining the same to positions substantially at right angles thereto throughout its various movements, mechanism for giving said carrier and said frame a reciprocatory movement, and apparatus for adjusting the path of reciprocation of said carrier.

9. In a loading machine, the combination with a carrier comprising spaced apart arms, of supporting structure for said carrier, a prop in a kerf in a mine wall, and means for operating said carrier to cause said arms to enter said kerf while straddling said prop and remove a block of material from the mine wall.

10. In a loading machine, the combination with a carrier, of an upright structure for guiding said carrier in its movements and confining the same to a right angle relation to said structure, a main supporting frame, means for lifting and lowering said carrier while retaining such relation, and means for thrusting forward said guiding structure relatively to said frame while said structure remains upright to cause said carrier to take a load of material from a mine wall.

11. In a loading machine, the combination with a carrier, of an upright guiding structure for maintaining said carrier substantially at right angles thereto for all positions of said carrier, a main supporting frame, rope gearing for controlling the elevation of said carrier, and means for operating said carrier relatively to said frame to take a load of material from a mine wall.

12. In a loading machine, the combination with a supporting frame, of a carrier, vertical guides laterally movable relatively to said frame, means movable along said guides for confining said carrier to a right angle relation with said guides, means controlling the elevation of said carrier, and means for moving horizontally forward said guides and carrier relatively to said frame to take a load of material.

13. In a loading machine, the combination with a carrier, of a main supporting frame,

upright spaced-apart guides mounted on said frame, guide blocks connected to the rear end of said carrier and confined to upright movements in said guides to hold said carrier in substantially right angle relation to said upright guides, means for controlling the elevation of said carrier along said guides, and apparatus for thrusting forward said guides and said carrier relatively to said frame to cause the carrier to move into position to take a load at its adjusted elevation.

14. In a loading machine, the combination with a carrier having spaced-apart arms, with an open space between them and vertical side pieces connected to the outside lateral edges of said arms adapted to enter kerfs in a mine wall, of guide blocks connected to the rear ends of said side pieces, guides for receiving said guide blocks, and hoisting mechanism comprising rope drums and ropes connected respectively to each of said guide blocks for controlling the position of said carrier along said guides.

15. In a loading machine, the combination with a carrier comprising a cross-piece at its rear end, of a supporting frame having a longitudinal recess in alignment with the space immediately above said cross-piece when said carrier is in its loading position, a guide frame for said carrier, and means for definitely positioning said carrier relatively to said supporting frame in said loading position.

16. In a loading machine, the combination with a carrier having a longitudinal slot, of a supporting frame having a recess in its upper surface in registry with the slot of said carrier when the latter is in loading position, and means for operating said carrier to take a load of material and move it to such loading position.

17. In a loading machine, the combination with a carrier adapted to receive a block of material directly from a mine wall, of a main frame, a supplemental frame for said carrier, a motor on said supplemental frame, a rope drum on the latter frame, gearing between said motor and said drum, a rope connected at its ends to the ends of said main frame and associated with said drum to hold said supplemental frame in place on said main frame, and guide pulleys on said supplemental frame for said rope.

18. In a loading machine, the combination with a main frame, of a supplemental frame, a carrier connected to said supplemental frame, a transverse shaft on said supplemental frame, rope drums mounted on the ends of said shaft, ropes associated with said drums respectively and connected at their ends to the main frame at both sides of said supplemental frame to hold the lat-

ter in place on said main frame, guides for said ropes on said supplemental frame, and power mechanism on said supplemental frame for transmitting motion to said shaft 5 and drums.

19. In a loading machine, the combination with a carrier, of a main supporting frame, a supplemental frame for said carrier, means for moving said supplemental frame and said carrier relatively to said main frame to cause said carrier to enter kerfs in a mine wall bounding a block of material and removing said block of material from the mine to a predetermined position relatively to said main frame, and mechanism comprising a rope for pulling the block of material from said carrier into loading position.

20. In a loading machine, the combination with a carrier, of means for operating said carrier to take a load of material, a rearwardly extending frame adapted to extend over the top of a mine car, a guide pulley mounted at the rear end of said frame, a rope engaging said pulley, and means acting on said rope to pull the material from said carrier into loading position on the mine car.

21. In a loading machine, the combination with a supporting frame, of an arm extending rearwardly from said supporting frame, a guide pulley on said arm, a rope associated with said pulley, a carrier on said frame, self-acting power mechanism for operating said carrier by moving the same into a kerf in an upright mine wall in position to receive a block of material from the mine wall above said kerf, devices connected to said rope for engaging directly the block of material on said scoop, and rope winding mechanism on said frame for exerting a pull on said rope to move said block of material off said carrier and over said frame into loading position on a mine car traveling on a mine track under said arm.

22. In a loading machine, the combination with a main frame, of an inverted U-shaped supplemental frame open from end to end, means for reciprocating said supplemental frame, a carrier on the supplemental frame, and means for pulling the load from said carrier into loading position through said supplemental frame.

23. In a loading machine, the combination with a truck, of a rotary frame pivoted to said truck, turn-table mechanism for rotating said frame, a main frame pivoted to said rotary frame, apparatus for lifting and lowering said main frame on its pivot, a supplemental frame slidably mounted on said main frame, a guide frame pivoted to said supplemental frame, a carrier mounted in said guide frame, hoisting mechanism for lifting and lowering said carrier, means for

reciprocating said supplemental frame, unloading apparatus, and means for tilting said guide frame together with said carrier. 65

24. In a loading machine, the combination with a supporting frame, of a supplemental frame pivotally connected thereto on a transverse axis, a scoop carried by said supplemental frame and guided along the latter for rectilinear adjustment in elevation, and means for tilting said supplemental frame on said transverse axis to secure tilting of said scoop at its adjusted elevation. 75

25. A mining and loading machine comprising supporting framework, a carrier mounted on said framework for rectilinear adjustment in elevation, means on said framework for holding said carrier at adjusted elevation, mechanism for effecting the dislodgment from a mine wall of a block of material onto said carrier from a space in a mine wall above said carrier, and means for operating said carrier to effect the transfer of the block of material away from the mine wall in a general horizontal direction to a position spaced therefrom in a general horizontal direction in a mine chamber. 80 85 90

26. In a mining and handling system, the combination with supporting framework, of a carrier mounted thereon to occupy substantially horizontal positions and for rectilinear adjustment in elevation, means for moving said carrier rectilinearly relatively to said framework to adjust the elevation of said carrier, mechanism for effecting the dislodgment of a block of material onto said carrier from a position in the mine wall 100 above said carrier, and means for operating said carrier to move the block of material in a general horizontal direction to a position spaced back from the mine wall.

27. In loading apparatus, the combination with a main frame, of a supplemental frame pivoted to said main frame for upward and downward movement of the forward portion of said supplemental frame, a carrier mounted on said supplemental frame for movement relatively thereto both upwardly and downwardly and in a general horizontal direction, means for moving said carrier rectilinearly to adjust the elevation thereof, means for reciprocating said carrier relatively to said supplemental frame in a general horizontal direction, and means for unloading material from said carrier out of the rear end thereof. 105 110 115

28. In loading apparatus, the combination with a supporting frame, of a traveling carrier mounted thereon for movement relatively thereto in advance of said supporting frame, means for reciprocating said carrier in a general horizontal direction by moving it forward in advance of said supporting frame and retracting it to its initial position relative to said frame, pulling mechanism 120 125

- adapted to be connected to a block of material on said carrier, and self-acting power mechanism for operating said pulling mechanism to effect the discharge of material 5 from said carrier out of the rear end thereof.
29. In loading apparatus, the combination with a carrier, of a chute directly back of said carrier, means for moving said carrier forward to take a load and retract the same 10 with the load to said chute, and means acting on the material to move the same off said carrier into said chute while said carrier remains stationary.
30. In loading apparatus, the combination with supporting framework, of a carrier mounted thereon for adjustment in elevation relatively thereto, means for moving said carrier forward relatively to said framework into position to take a load and retract 15 said carrier with said load, and mechanism comprising locking worm gearing for rectilinearly adjusting the elevation of said carrier whereby said carrier is locked at adjusted elevation by said worm gearing.
31. The combination with supporting framework, of a load-gathering device mounted on said framework for rectilinear adjustment in elevation, means for reciprocating said load-gathering device in a general horizontal direction at adjusted elevation, and mechanism acting on the material while on said load-gathering device to move such material along such device out of the 20 rear end thereof.
32. In loading apparatus, the combination with a frame comprising a chute, of a carrier open at its rear end and adapted to register with the forward end of said chute, means for rectilinearly adjusting the elevation 25 of said carrier, means for reciprocating said carrier in a general horizontal direction at its adjusted elevation, and mechanism acting on the material on said carrier to move the same rearwardly out of the rear end of said carrier into said chute during the registry of the rear end of said carrier with the forward end of said chute.
33. In loading apparatus, the combination with a main frame, of a supplemental frame, a scoop connected to said supplemental frame to move bodily therewith, means for reciprocating said supplemental frame together with said scoop for the purpose of gathering loads of material, and means acting on the material in said scoop to move such material out of the rear end of said scoop irrespective of whether said scoop is stationary relative to said main frame or moving relatively to said main frame.
34. In loading apparatus, the combination with a main frame, of a supplemental frame comprising a chute, a load-gathering device supported by said supplemental frame, means for reciprocating said load-gathering device, mechanism for moving material from 35 said load-gathering device into said chute while said load-gathering device is in stationary position adjacent the forward end of said chute, and means for moving said supplemental frame together with said load-gathering device laterally on said main frame. 70
35. In loading apparatus, the combination with a main frame, of a supplemental frame pivoted to said main frame for movement relatively thereto on an upright axis, a scoop supported by said supplemental frame for movement bodily therewith in a general horizontal direction, means for moving said supplemental frame on such upright axis to 75 effect lateral arcuate movement of said scoop, means for rectilinearly adjusting the elevation of said scoop, mechanism for moving said scoop forward in a general horizontal direction to take a load of material 80 from an upright mine wall at the adjusted elevation and retract said scoop with the load thereon, and mechanism for discharging the load of material from said scoop and moving such material relatively to said main frame toward loading position. 85
36. In loading apparatus the combination with a chute, of a scoop open at its rear end, means for rectilinearly adjusting the elevation of said scoop above and below 90 the forward open end of said chute, means for reciprocating said scoop in a general horizontal direction at its adjusted elevation, and mechanism for unloading said scoop into said chute independently of the main frame toward loading position. 95
37. In loading apparatus, the combination with a main supporting frame, of a supplemental frame pivotally mounted on said main frame for lateral movement in an arc relatively to said main frame on an upright axis, a scoop mounted on said supplemental frame, means for reciprocating said scoop relatively to said main frame in its various arcuate positions for the purpose of gathering loads of material, and means operable independently of the reciprocations of said scoop for acting directly on the material on said scoop to unload such material 105 out of the rear end of said scoop. 110
38. In loading apparatus the combination with a supporting frame, of a scoop mounted thereon in position to move horizontally to receive a block of material having a lower horizontal surface, means permitting adjustment of said scoop to various radial positions, means for operating said scoop by projecting horizontally relatively to said frame while being retained in position to engage the lower horizontal surface of such block of material and carry such block of material in such position, and mechanism operable independently of the 115 120 125 130

forward movements of said scoop for unloading the material in a general horizontal direction out of the rear end of said scoop.

- 5 39. In loading apparatus, the combination with a supporting frame, of a scoop open at its rear end, means for confining said scoop to positions for engaging a block of material having a lower horizontal surface and carrying such block of material with its lower surface in an approximately horizontal plane, means for reciprocating said scoop rectilinearly in a general horizontal direction while being maintained in 15 such position, and mechanism for positively moving the material off the scoop out of the rear end thereof in a general horizontal direction independently of forward movement of said scoop.
- 20 40. In loading apparatus, the combination with a supporting frame provided with a chute, of a scoop mounted on said frame for adjustment in elevation above and below the forward end of said chute, means 25 for reciprocating said scoop horizontally at adjusted elevation to gather a load from an upright mine wall, and mechanism for moving the material in said scoop out of the open rear end thereof into said chute independently of forward movement of said scoop and while said scoop occupies a position registering with said chute.
41. In a loading machine, the combination with a supporting frame comprising a 35 horizontal chute, of a scoop confined to horizontal positions on said supporting frame, means for adjusting said scoop rectilinearly in elevation above and below the forward end of said horizontal chute while said 40 scoop is confined to horizontal positions, means for moving said scoop forward relatively to said frame at the adjusted elevation of said scoop for the purpose of taking a load, and means for moving the load out 45 of said scoop into said chute while said scoop is in horizontal alinement with said chute and moving such load horizontally along said chute out of the rear end thereof.
- 50 42. In a loading machine, the combination with a supporting frame, of a scoop mounted thereon for rectilinear adjustment in elevation, means for reciprocating said scoop at its adjusted elevation by movement 55 thereof in a general horizontal direction to gather loads from an upright mine wall at various elevations, a chute on said frame and extending horizontally back of said scoop when the latter is in initial position, and means for transferring material from said scoop along said chute toward loading position.
43. In a loading machine, the combination with a supporting frame, of a scoop 60 open at its rear end, means on said frame
- for guiding said scoop rectilinearly to various elevations, mechanism at the rear end of said scoop connected to said guiding means to confine said scoop to approximately horizontal positions at the various elevations 70 thereof, means for moving said scoop forward in a general horizontal direction at its adjusted elevation to move said scoop into a mine wall a distance approximately equal to the entire length of said scoop, a chute 75 on said frame, and means for moving the material on said scoop out of the rear end thereof and horizontally along said chute into position for loading onto a mine car.
44. In a loading machine, the combination with a main frame, of a supplemental frame pivotally connected to said main frame for arcuate movement relatively thereto on an upright axis, a scoop connected to said supplemental frame and extending in advance thereof in horizontal positions at various elevations, means for rectilinearly adjusting the elevation of said scoop, means for reciprocating said scoop to reach forward horizontally for loads in 85 various arcuate positions at various elevations at an upright mine wall, a chute back of said scoop and in alinement therewith in a general horizontal direction when said scoop is in a predetermined position at a 90 predetermined elevation, and means for transferring the material in said scoop out of the rear end thereof into the forward end of said chute and horizontally along the latter toward the rear end thereof to loading 95 position.
45. In a loading machine, the combination with a main frame, of a supplemental frame pivoted on said main frame on a transverse axis for up and down tilting 100 movement, a scoop connected to said supplemental frame to extend in advance of that end thereof remote from said axis and transversely of such axis, means for tilting said supplemental frame to adjust the inclination of said scoop, a tertiary frame connected to said scoop and movable bodily therewith relatively to said supplemental frame, a chute comprising portions of said supplemental and tertiary frames, means 105 for operating said scoop to gather a load, and mechanism for effecting the transfer of material from said scoop into said chute and along the latter toward loading position.
46. In a loading machine, the combination with a main frame, of a supplemental frame pivotally connected to said main frame for arcuate movement relatively thereto on an upright axis, a scoop connected to 110 said supplemental frame and movable arcuately therewith, a chute back of said scoop and in alinement therewith and extending horizontally and longitudinally of said main frame from the front toward the rear 115

thereof, means for rectilinearly adjusting the elevation of said scoop, propelling mechanism for moving said frames forward to force said scoop in a general horizontal direction at adjusted elevation into material to be loaded, and mechanism adapted to travel along said scoop relatively thereto for transferring the material out of the open rear end of said scoop into the forward open 10 end of said chute and along the latter toward loading position.

47. In a mining and loading machine, the combination with a supporting frame comprising a chute open at its forward end, of a reciprocable carrier movable back and forth from a position at the forward portion of said chute, means for dislodging material from a mine wall in advance of said frame, and means for operating said carrier for receiving the dislodged material directly from its position in the mine wall and transferring such material to the forward open end of said chute.

48. In a mining machine, the combination with a frame, of a chute mounted thereon, means for adjusting the position of said chute adjacent the mine wall, and means for taking a large block of solid material from its position in the mine wall and 30 delivering it intact directly therefrom into said chute.

49. In a mining and loading machine, the combination with a frame having an inclined chute open at its forward end and at its rear end, of mechanism for dislodging material from a mine wall for movement into the forward open end of said chute, and reciprocable mechanism mounted on said frame in position to transfer material along said chute toward loading position. 40

50. In a loading machine, the combination with supporting framework, of a platform mounted on said framework and movable up and down rectilinearly relatively to said framework, means for adjusting the elevation of said platform rectilinearly relatively to said framework while maintaining said platform in a substantially horizontal plane, and means for operating said platform relatively to said framework in a general horizontal direction to effect the transfer toward loading position of a block of material bounded at the bottom, top and sides by kerfs while in its native bed. 50

In testimony whereof I have signed my name to this specification, in the presence of two subscribing witnesses, on this 1st day of August, A. D. 1913.

EDMUND C. MORGAN.
